ORNAMENT WITH LIGHT EFFECTS

Filed July 8, 1941

GERHART WEISS,
INVENTOR,

by *Julian J. Wittel*,
his Attorney.

UNITED STATES PATENT OFFICE

2,345,517

ORNAMENT WITH LIGHT EFFECTS

Gerhart Weiss, New York, N. Y., assignor of one-half to Paula Karpfen, New York, N. Y.

Application July 8, 1941, Serial No. 401,411

3 Claims. (Cl. 240—10.1)

This invention relates to ornaments to be used in decorating premises for certain occasions, or in general, and particularly it relates to ornaments or decorations to be used on Christmas trees, and has for its main object to provide such an ornament or decoration with a novel light effect.

Other objects of this invention are: to provide a device as characterized hereinbefore which will be simple in construction, inexpensive to manufacture, easy to apply or to remove, easy to operate, and which will operate as soon as it is connected into any of the usual house electric circuits.

Still further objects of this invention will be apparent as the specification of the same proceeds.

In the drawing forming a part of this specification and accompanying the same:

Fig. 1 is a front elevation of an embodiment of my novel ornamental device;

Fig. 2 is a sectional elevation, the section being taken on the line 2—2 of Fig. 1;

Fig. 3 is an elevation of a rotating cylindrical body used in my invention, being shown on an enlarged scale, and

Fig. 4 is a sectional elevation thereof, the section being taken on the line 4—4 of Fig. 3.

Referring now to the drawing more in detail by characters of reference, the embodiment of my device illustrated in the drawing shows a star shaped ornamental device, particularly designed for Christmas tree tops, having a main star shaped hollow body, generally indicated by the numeral 10 and being of the ornamental contour, formation and design as illustrated in Figs. 1 and 2.

The star shaped hollow body has inclined ornamental opaque circumferential right hand walls 11, and similar left hand walls 12, and the rear face thereof is closed by an opaque rear wall 13, while the front is formed by an opaque wall 14 having a plurality of perforations or holes 15. Of course the back wall or any other wall may have similar perforations.

An inner wall or lining 16 placed back of the perforated wall 15, said inner wall 16 being of translucent or of a reduced transparent character. As an example, the front wall 14 may be made of a board of plastic material and the inner lining wall 16 of translucent tissue paper.

In the lower center of the star shaped hollow body 10 is arranged a tubular extension 17 for

the same, into which is set a tubular socket or securing piece 18 for my device.

The lower portion or socket 19 of an elongated electric light bulb 20 is secured in the upper part of the tubular extension 17, the terminations or posts 21 and 22 of the electric bulb being connected to the wires 23 and 24, respectively, of a usual electric connector plug 25.

For the best effect I employ a light bulb 20 of elongated shape having a single elongated filament 26 being supported by the wire 27, as it is well known in this art.

A slightly resilient wire coil 28 is pulled over the outside of the bulb 20 tightly engaging the same and being secured thereon by its friction, said coil 28 terminating in an upper pin 29. A cylindrical body, generally indicated by the numeral 30, and being of the construction to be described presently, is rotatably suspended on the pin 29, as by a cup shaped bearing element 31 of greatly reduced frictional resistance, as of glass, set into the top disc 32 of the cylindrical rotatable body 30.

In the embodiment shown, the cylindrical body 30 is constructed as follows:

From an upper top disc 32 a plurality of opaque strips 33 depend forming a hollow cylindrical body and having the spaces 34 left between them. To secure the device in this shape and still permit the light to pass through the spaces 34, upper and lower securing strips 35 and 36 are arranged, made of any suitable transparent material, like a cellulose product, "Cellophane," etc. Further similar securing rings 37 may be arranged on the inside of the device being of similar material to that of securing rings 35 and 36.

Propelling means 38, similar to the blades of a fan are separated from the material of the top disc 32 and bent upwardly in a manner known to those versed in this art.

For better balancing and further securing the device, wire ring 39 may be secured around the lower end thereof.

As will be seen in Fig. 2 the cylindrical device 30 will be placed over and around the electric bulb 20 by permitting it to rest through its glass bearing cup 31 on the pin 29.

The operation of my device is as follows:

My novel ornament will be secured at the place it is desired to use the same by its tubular lower end 18, as by pushing the same over the tip of a Christmas tree. Plug 25 is then inserted into the electric outlet, and the bulb will be illumi-

nated. The hot air produced by the heat of the bulb will ascend in the device, as indicated by the arrow 40 and the air striking the upper fan blades 38 will rotate the cylinder 30. Through the operation of the opaque strips 33 and the free spaces 34 in the cylinder, the light will alternatingly play on the various perforations 15 in the face 14 of my device, and thereby an effect similar to stars being lit and being extinguished in rotation will be produced. The opaque wall 14 may be made deep blue in color for this purpose to imitate the sky.

Appropriate upper and lower openings 41 and 42 may be arranged in the hollow body 10 to aid in the production of an air current 40.

The translucent inner wall or lining 16 to the rear of the perforated wall 14 is highly desirable to be employed, since without that the effect of rising and extinguishing stars will not be perfect.

It is obvious that instead of the hollow star shape used in the embodiment of my invention shown in the drawing, other hollow shapes may be used, as for instance, an angel for the tip of a Christmas tree, the stars lighting and extinguishing on the dress of the angel. Similarly, human or animal figures, or other ornamental hollow bodies may be employed on my rotating cylinder 30 having appropriate apertures in their walls for a novel light effect.

It also will be obvious that instead of building the cylindrical body 30 of independent opaque strips 33, the same may be made of a hollow transparent cylinder, as for instance, of "Cellophane" and the opaque strips 33 may be painted thereon. Instead of the strips 33, an opaque helical design, or any other opaque parts, may be painted thereon and, in general, a rotating body 30 may take other shapes and may have other designs, the main requirement being that it should have alternate transparent and opaque elements.

Openings 41 and 42 may be provided in the top and bottom, respectively, of hollow body 10 to aid in forming the air current 40.

What I claim as new, is:

1. In an ornamental device with light effects for Christmas trees and the like, having a housing, a heat producing source of light in said housing, a rotatable member around said source of light having alternate opaque and transparent portions, and openings in the wall of said housing to create said light effects, said housing having wide vertically set front and rear walls, substantially identical in contour, closely set to one another, inwardly inclined circumferential walls around said front and rear walls to complete said housing, a tube downwardly extending through the bottom center of the housing, open at both ends, and communicating with the interior of the housing, said heat producing light source being in the form of an elongated electric bulb set into said tube and projecting into said housing near to its top, electrical connections for 15 said bulb introduced through the wall of said tube means over said bulb responsive to its heat to rotate said member, the ornamental device being adapted to be secured on the tip of a Christmas tree, or the like, by pushing the lower 20 part of said tube thereover, said light effect producing openings being in said wide front wall.
2. In an ornamental device, as set forth in claim 1, cooperating openings in the top and in the bottom, respectively, of said housing, one set 25 being in said inclined end walls in front of, and the other set to the rear of, the center plane of the device, to create a predetermined air current therethrough, by the action of the heat of said light source, said means to rotate said member being actuated by said air current.
3. In a device, as set forth in claim 1, said front wall being of blue colored translucent material to imitate the sky, and a translucent colorless sheet placed back of its openings for aiding in the effect of scintillating stars.

GERHART WEISS.
